WINDOW CONSTRUCTION

Edward F. Chaffee, Syracuse, N. Y., assignor to
The O. M. Edwards Company, Inc., Syracuse,
N. Y., a corporation of New York

Application February 10, 1937, Serial No. 125,102

4 Claims. (Cl. 189—76)

This invention relates to window constructions, particularly for vehicles, as the cars of stream line trains, and has for its object a weather tight mounting for the sash in the frame, and more particularly a weather tight mounting for the rounding corners of the sash in the rounding corners of the window frame.

It further has for its object a weather tight mounting for a sash in a window frame with rounding corners, which weather strip is composed of flexible resilient material, as rubber, and is in the form of a channel fitting in the channel of the window frame and receiving within it the sash, the weather strip having beads or heads at the margin of its side walls, which beads are pressed tightly against the sash or the glass thereof forming a weather tight glazing strip, with the mounting being so constructed that when the strip is bent around the corners of the sash and the frame, the beads at the corners lie snugly and uniformly, without buckling or distortion, along the sash and the window frame.

The invention consists in the novel features and in the combinations and constructions herein-after set forth and claimed.

In describing this invention, reference is had to the accompanying drawing in which like characters designate corresponding parts in all the views.

Figure 1 is a fragmentary isometric view of a window construction embodying this invention.

Figure 2 is an enlarged fragmentary isometric view of the weather strip mounting for the sash.

Figure 3 is an elevation of the U-shaped weather strip before applied to the frame and sash.

This construction is particularly designed for sashes that are immovably mounted in the window frame.

1 designates the window frame, which is mounted in the window openings of the car body in any suitable manner, this frame being usually formed of metal to provide a channel 2 for receiving the sash, one wall 3 of the channel being demountable for the purpose of replacing the sash in the window or removing it therefrom.

By sash is meant a glass pane, single or double, with or without a marginal frame.

As here illustrated, the demountable side 3 fits in a groove 4 in the window frame beyond the bottom of the channel 2 and is held in the groove by a screw 6.

8 designates the sash frame, this being usually formed of metal and being formed with a channel 9 for receiving the margin of the glass 10. As

here shown, the sash is formed with a double glass pane with a spacer 11 between them.

The construction of the sash frame per se forms no part of this invention.

The margins of the glass pane may fit in an inner weather or glazing strip 12 in the channel of the sash frame, as shown in the application of Roy T. Axe, Serial No. 103,560, filed October 1, 1936.

13 designates the flexible and resilient weather tight mounting strip for the sash in the window frame.

The window frame and the sash are formed with rounding corners, and this invention relates to the construction of the weather strip, whereby the weather strip, when bent, around the rounding corners, fits, without distortion, against the sash or the glass thereof. The strip 13 is U-shaped in cross section and fits into the channel 2, and the sash frame 8, when in position, snugly fits the weather strip and presses it against the sides and the bottom of the channel 2. The sides of the U-formation of the strip 13 are provided with headed or beaded portions 14 located beyond the inner edges 15 of the side walls of the channel 2 of the window frame, these beaded portions 14 pressing against the sash frame or the glass thereof. The beaded portions coat with the edges of the side walls of the channel 2 of the window frame, so that the beaded portions are pressed against the sash or the glass thereof.

The mounting strip 13 is made up in straight strips U-shaped in cross section, and when applied to the window and sash frame is bent around the rounding corners of the channel 2 of the window frame and the rounding corners of the sash frame. Ordinarily, this would cause distortion and buckling of the strip at the corners, and particularly distortion of the beaded portions 14 at the corners, so that the beaded portions would not lie snugly against the sash or the glass thereof, and the margins of the side walls of the channel 2 of the window frame.

In order to cause these beaded portions 14 to snugly, without distortion, lie against the sash or the glass thereof and against the margins of the side walls of the channel 2 around the corner portions thereof, the strip 13 at the corner portions

thereof is formed with transverse slits 16 through the bottom portion of the channel formation thereof, the slits extending partly into the side walls of the U-formation of the strip, so that when the strip is bent around the corners of the sash and the frame, these slits open and permit the U-shaped strip 13 to bend, without dis-

- torting the beaded portions 14. Hence, when the installation is complete, the beaded portions, which serve as glazing strips, lie uniformly on the sash or the glass and are continuous or undivided without wrinkling and distortion, so that the sash is snugly glazed throughout its entire extent and wind and weather prevented from beating in crevices at the inner and outer edges of the beaded portions.
10. What I claim is:—
1. In a window construction, the combination with a window frame in the form of a channel, the frame having rounding corners, and a sash mounted in the channel and having rounding corners; of a mounting and weather strip in the channel in which the sash is mounted, said strip being in the form of a channel fitting the channel in the frame and having the edges of its side walls in the form of beads pressing against the sash and the outer edges of the side walls of the channel of the frame and forming glazing strips, the channel-shaped strips being formed with transverse slits in the bottom portion thereof at the corners of the window frame and the sash.
  2. In a window construction, the combination with a window frame in the form of a channel, the frame having rounding corners, and a sash mounted in the channel and having rounding corners; of a mounting and weather strip in the channel in which the sash is mounted, said strip being in the form of a channel around the periphery of the sash and embracing the sash, the strip fitting the channel in the frame and having the edges of its side walls in the form of beads pressing against the sash, said strip being formed with transverse slits in the bottom portion thereof at the corners of the window frame and the sash.
15. In a window construction, the combination with a window frame in the form of a channel, the frame having rounding corners, and a sash mounted in the channel and having rounding corners; of a mounting and weather strip in the channel in which the sash is mounted, said strip being formed with transverse slits in the bottom portion thereof at the corners of the window frame to cause the beaded portions to press evenly against the sash and the window frame at the corners, without distortion.
20. In a window construction, the combination with a window frame in the form of a channel, the frame having rounding corners, and a sash mounted in the channel and having rounding corners; of a flexible cushion mounting and resilient weather strip in the channel in which the sash is mounted, said strip being in the form of a channel and fitting the channel in the frame and having the edges of its side walls in the form of beads coacting with the walls of the channel of the frame to press the beads against the sash, said strip being formed with transverse slits in the bottom portion thereof at the corners of the window frame to cause the beaded portions to press evenly against the sash and the window frame at the corners, without distortion.
25. In a window construction, the combination with a window frame in the form of a channel, the frame having rounding corners, and a sash mounted in the channel and having rounding corners; of a flexible cushion mounting and resilient weather strip in the channel in which the sash is mounted, said strip being initially straight in the form of a channel in cross section and being fitted in the channel of the frame and around the corners thereof and embracing the margin of the sash, the strip having beads at the edges of its side walls pressing against the sash, the strip being constructed to cause the beads to be continuous at the corners of the sash and the frame, without buckling or distortion.

EDWARD F. CHAFFEE.
